UNITED STATES PATENT OFFICE.

GEORGE W. GOUGH, OF EAST HAMPTON, CONNECTICUT.

IMPROVEMENT IN WHEELS FOR TOYS.

Specification forming part of Letters Patent No. 178,290, dated June 6, 1876; application filed April 26, 1876.

To all whom it may concern:

Be it known that I, GEORGE W. GOUGH, of East Hampton, in the county of Middlesex and State of Connecticut, have invented a new Improvement in Wheels for Toys; and I do hereby declare the following, when taken in connection with the accompanying drawings and the letters of reference marked thereon, to be a full, clear, and exact description, and which said drawings constitute part of this specification, and represent, in—

Figure 1, a side view, and in Fig. 2 an end view, showing the transverse section of one wheel.

This invention relates to an improvement in wheels for that class of toys which are made to be trundled or rolled, the object being to produce a ringing noise by the trundling.

The invention consists in constructing the wheels in the form of bells, attached to the axle, so as to revolve when the toy is trundled, and with a ball or other device within the bell, so that the trundling of the toy produces a ringing sound from the wheels.

A is the axle; B, the platform or body. To each end of the axle a wheel, C, is attached, either so

as to revolve with the axle or to revolve independent thereof, as may be desired. These wheels are made hollow and of any suitable material which possesses sufficient resonance to produce a ringing sound. Openings are made through the shell of the wheel, as at a, or otherwise, and the wheels may be of any desirable shape in transverse section, or made so as to closely resemble other wheels. Within the wheel a ball, D, is placed, which, as the wheel revolves, tumbles within the wheel and produces the desired ringing sound; but other devices may be applied to produce this sound, it only being essential to the invention that the wheels be what may be termed "bells."

I claim—

The herein-described wheel for toys, consisting of a hollow shell, formed of resonant metal, arranged upon the axle of the toy, and provided with a ball or hammer within, to sound the bells as the wheels are revolved, substantially as described.

GEORGE W. GOUGH.
